UNITED STATES PATENT OFFICE

CARROLL E. ORR, OF ORANGE, NEW JERSEY, ASSIGNOR TO ELEVATOR SUPPLIES COMPANY, INC., OF HOBOKEN, NEW JERSEY, A CORPORATION OF NEW JERSEY

CIRCUIT CONTROLLING MECHANISM

Application filed June 6, 1928. Serial No. 283,331.

This invention relates to elevator signals and particularly to those signals or indications which are employed for denoting the position and progress of the elevators, so that 5 persons in any elevator or at any floor where the indications are displayed may know the exact location and direction of motion of the associated elevator at all times during its movement.

10 The present invention consists in certain novel features and improvements in construction and method of operation over the system described and claimed in the application of Cyrus W. Bassett and Harold J. Fear, 15 filed in the United States Patent Office on October 27, 1925, and bearing Serial No. 65,086, and also consists in improvements on the system described and claimed in the application of Cyrus W. Bassett, Serial No. 20 356,219, filed April 18th, 1929.

One of the principal features of such systems as those above referred to resides in the provision of means whereby the progress of the elevator in one direction causes the progressive illumination of a series of index elements, arranged in file formation, together with means for immediately reversing the direction of progress of the column of light thus formed upon the reversal of the direction of motion of the elevator, whether such reversal of direction takes place at the limit of the elevator's path of travel or at any intermediate point.

The invention further relates to systems 35 wherein means are provided whereby such a reversal of direction of the elevator's movement at any point in its travel causes an extinguishing of the light produced by the aforesaid index elements, with the exception 40 of the last illuminated index element, and a simultaneous illumination of all the index elements theretofore unilluminated together with the continuation of the illumination of the aforesaid last illuminated index element. 45 The effect produced by this novel means, from the observer's point of view, is the effect obtained by taking an illuminated column and turning it over through an arc of 180° about its foremost element as an axis, whereby the 50 illuminated column undergoes a complete

change of position and at the same time an end to end reversal.

In the preferred form of invention as illustrated herein, electric lamps constitute the index elements, and the illuminated column 55 is that which is produced by the successive and progressive illumination of the electric lamps as the associated elevator proceeds from floor to floor in either direction, the means for producing such progressive energization of the floor designating lamps consisting of commutator mechanism of novel construction which operates to close the circuits to successive lamps in proper sequence, and further operates to hold such circuits 60 closed until such time as the elevator reverses its direction of travel; at which time the novel commutator means operates to cause an immediate breaking of all said circuits, with the exception of the circuit last closed, and 65 a simultaneous closing of all remaining circuits not theretofore closed.

Other objects and advantages to be derived from the use of the novel mechanism disclosed herein reside in the specific construction and arrangement of the parts, and will become more apparent as the description progresses; reference being had to the accompanying drawings wherein Figure 1 is 75 a vertical section of a building having several floors served by a bank of elevators, one of which is shown in this figure.

Figure 2 is a view on a larger scale of the commutator mechanism indicated in Fig. 1, the casing of the commutator being removed 85 so as to reveal the construction of the moving parts.

Figure 3 is a schematic illustration of the electrical parts, including the commutator, 90 and the circuits involved in the preferred embodiment.

Figures 4, 5 and 6 are schematic representations showing the appearance of the indicating units under conditions different 95 from those assumed to be obtaining in Fig. 3.

Figure 7 is a view of a portion of the mechanism shown in Fig. 2, including the circuit reversing mechanism. 100

Figure 8 is a side view of the parts shown in Fig. 7.

Figure 9 is a section on line 9—9 of Fig. 7.

5 Fig. 10 is a section on line 10—10 of Fig. 2.

In Fig. 1 an elevator 9 represents one of a group of elevators adapted to travel up and down an elevator hatchway 10 under 10 the control of a suitable driving motor and associated hoisting mechanism, part of which is represented by the sheave 11; the elevator 9 constituting a means for receiving and discharging passengers at the floors 15 1 to 8 shown in Fig. 1. The number of floors, of course, has no particular significance so far as the novelty of the invention is concerned, eight floors being assumed merely for convenience of illustration.

20 There is preferably located at each of the floors a panel 12—13 etc. upon each of which is mounted a group of floor indicating elements as 20 to 27 inclusive, for example. As illustrated herein each of the index elements 20 to 27 is in the form of an electric lamp, the lamps being arranged in file formation one above the other so as to produce when illuminated a single column of light. The column of light may be of uniform intensity or it may consist of alternately light 25 and dark sections, depending upon whether or not a focusing glass or other screen of translucent qualities is placed in front of the row of lamps. Furthermore, although only 30 the index elements for the single elevator 9 are shown in the drawings it is to be understood that in actual practice each indicating panel may have as many of these columns of lamps as there are elevators in the 35 building. However, since the illustration of such additional columns of lamps and the operating means therefor would constitute mere duplication over the illustrations in Figures 1 to 6 inclusive, it is believed unnecessary to include such additional illustration.

The first floor lamp 20 on each panel 12—13 etc., is multiplied to the lowermost stationary brush unit 30 (see Fig. 3) on the 40 commutator mechanism. The second lamp 21 is multiplied to brush unit 31, and so on, there being one brush unit for each floor lamp. Each brush unit consists of a pair of brushes, as 34 and 34a (Fig. 10), each of 45 which is mounted so as to engage successively the strips 40 to 44 as the latter travel back and forth in response to the travel of the elevator. In this connection a feature of the construction is the arrangement of 50 the brushes in staggered formation, with the right-hand brush of each pair disposed slightly in advance of the left member of the pair, as indicated best in Fig. 2. The 55 advantage of this staggered arrangement is that it eliminates arcing between the brushes

on the one hand and the strips 40 to 44 on the other, and also prevents undesired momentary interruptions of the circuits controlled thereby as the brushes pass off and on successive strips. By staggering each 70 pair of brushes, the leading brush of the pair reaches the succeeding contact strips before the trailing brush leaves the preceding strip, (see Fig. 11) thereby accomplishing the above-mentioned purposes.

75 Principal among the novel features of the commutator mechanism is the provision on the elongated carriage 38 (constituting the moving portion of the commutator structure) of five current conducting bars, or strips, of varying lengths and mounted on insulating bed 39 (see Fig. 10) of suitable material; the strips comprising first a central conducting strip 40, then a pair of relatively short conducting segments 41 and 42 (there being one on either side of central strip 40 and suitably spaced therefrom) and finally a second pair of relatively lengthy conducting strips 43 and 44, there being one 80 on either side of the central trio of conducting segments, as shown in Figures 3 to 6 inclusive. The purpose and advantage to be derived from this novel construction and arrangement of current conducting members 85 will become apparent as the description 90 proceeds.

95 Suitable means for moving the carriage 38 in synchronism with the elevator 9 are provided, and as illustrated herein consist of a 100 chain 45 passing over a sprocket actuated by sheave 11, a second sheave 46, suitable speed reducing mechanism 47, and cable 48 extending substantially the entire length of the hatchway 10 and connecting at its lower end by suitable coupling attachments 49 to a rack 50 which in turn connects at its lower end by an adjustable coupling bolt 51 with the weighted carriage 38 on which the conducting strips 40 to 44 inclusive are mounted. As 105 shown best in Figs. 2 and 10, the carriage 38 is provided with rollers 53—54 permitting free longitudinal movement along the guides 55 and 56 respectively, the latter being suitably secured to the wall of casing 57. Traveling with the segments 40, 41 and 42, and in 110 sliding engagement with stationary feed bars 107, 108 and 109 is a set of brushes 207, 208 and 209, (see Figs. 2, 3 and 10) suitably secured to the carriage 38, and insulated therefrom.

115 A novel mechanism whereby every change in the direction of travel of the elevator 9 (and consequently of the cable 48) produces a reversal of the circuits controlled by the commutator segments 40 to 44 inclusive is 120 illustrated in Figures 2, 7, 8 and 9, and consists principally of a gear 60 adapted to mesh with the teeth on the rack 50, a switch member 75 and a disk 78 so constructed as to be capable of only a predetermined degree of 125 130

rotation, the exact amount of which depends upon the length of the bell cranks 63 and 64 and their points of connection with the pins 65 and 66 respectively, the latter projecting 5 from the side of disk 78.

The switch member 75 is mounted to oscillate on the shaft 76 and has keyed thereto a second disk 77 on the outer face of which is mounted the disk 78 with which is associated the gear 60. A friction connection is provided between the gear 60 on the one hand and the disks 78, 77 and switch member 75 on the other, consisting preferably of the spring pressed pins 80 passing through the 10 disk 78 and threaded into the disk 77. With this construction the routine rotation of the gear 60 in response to the longitudinal movement of the rack 50 does not in any degree disturb the stationary condition of the disks 15 78 and 77 and hence of the switch member 75, until the rack 50 reaches its limit of movement with the arrival of the elevator at the lower terminal. At such time the bumper 67 is designed to come into shifting engagement 20 with the bell crank 63, moving it into the position shown in full lines in Fig. 2. When the elevator arrives at the opposite terminal, however, the engagement of the opposite bumper 67' with the opposite bell crank 64 25 will cause it to shift to the dash line position shown in Fig. 2. This produces a shifting of the disk 78 and hence of the switch member 75 to its opposite position shown in Figures 5 and 6.

30 In the position of the parts as shown in Fig. 2, commutator carriage 38 has reached its lowermost limit of travel (assumed for convenience to be the point reached when the elevator is at the first floor level) in which position the bumper 67 on the rack 50 has caused a shifting of the bell crank 63 to the position shown in full lines in Fig. 2; the corresponding position for the switch member 75 being as shown in Figs. 3 and 4.

45 Now, if the elevator reverses its position at an intermediate point, the consequent reversal of the direction of rotation of gear 60 will produce through the instrumentality of the friction exerting pins 80, a corresponding 50 partial rotation of the disks 78 and 77 (and hence of the switch member 75) to their opposite position, the oscillation of the disks 78, 77 and 75 ceasing as soon as the rotation of the outer disk 78 carries the pins 65 and 55 66 to their opposite limits of arcuate movement as determined by the length of the arms and slots on bell cranks 63 and 64.

60 From the foregoing it is apparent that whenever the elevator is ascending the switch mechanism is in the position shown in Fig. 2 and the switch member 75 is in the position shown in Figures 3 and 4, and that whenever the elevator reverses its direction of travel the switch mechanism will be shifted to the 65 position shown in dash lines in Fig. 2, and

the switch member 75 to the position shown in Figures 5 and 6; and furthermore, such shifting of the parts will occur whether the reversal of direction takes place at the limit of travel or at any intermediate point.

Having now described the various parts entering into the operation of the system a description of their inter-relation and method of operation will now be carried through. Considering the conditions to exist as shown in Fig. 2, that is, the elevator 9 standing at the first floor after having made a downward trip, bumper 67 in contacting with the bell crank 63 has just caused switch member 75 to be thrown to the position shown in Figures 3 and 4, thereby bringing its conducting surface 100 into electrical connection with the fingers 101 and 102 (see Fig. 3). Under these same conditions the disposition of the carriage 38 is such as is indicated in Fig. 3 wherein the central segment 40 is in engagement with the brush 30 and all other brushes are in engagement with the elongated segment 43. In this position of the parts a circuit is closed to the lowermost index element 20 representing the first floor, the circuit passing from the plus feed thru conductor 105, index lamp 20, conductor 106, brush 30, segment 40, traveling brush 207, stationary feed bar 107, and back to the negative feed by way of conductor 110. At the same time the circuit to the index element 20 is maintained by reason of the presence of the circuit holding conductor 117, the circuit passing as follows: From the plus feed thru conductor 105, index lamp 20, conductor 106, brush 30, conductor 117, finger 101, conducting surface 100 of the switch member 75 and back to the negative feed by way of the central finger 120 and conductors 121 and 122. At the same time, inasmuch as there is no energized conductor connecting with the elongated segment 43, the index elements governed by the brushes 31 to 37 inclusive are de-energized. It is therefore apparent that lamps 21 to 27 inclusive on the panels at each floor are extinguished while the lamp 20 on each panel is illuminated as an indication that the car is standing at the first floor.

115 As the car moves upwardly towards the second floor the corresponding upward movement of the carriage 38 first brings short segment 42 into engagement with the brush 30 thereby transferring the circuit through the lamp 20 to the said segment 42 as a shunt around the central segment 40; the circuit through conductor 117 being retained also. As the car arrives at the second floor the central segment 40 has arrived opposite the brush 31 and the elongated segment 44 opposite the brush 30. The engagement of the segment 40 with the brush 31 closes a circuit to the index element 21 on each panel, the circuit passing from the plus 120 125 130

feed thru conductor 105, index lamp 21, conductor 115, brush 31, segment 40, traveling brush 207, stationary feed strip 107 and back by way of conductor 110 to the negative feed.

Now, as the car proceeds upwardly toward the third floor the circuit to the index lamp 20 is maintained as traced above, the circuit to the index lamp 21 is transferred from the path above traced to the following path: 10 from the plus feed through conductor 105, index lamp 21, conductor 115, brush 31, conducting segment 42, traveling brush 209, stationary feed strip 109, conductor 145, finger 102, conducting surface 100 of switch member 75, and thence back to the negative feed by way of return brush 120 and conductors 121 and 122. The short segment 42, therefore, is instrumental in the maintenance of a circuit to the index lamp 21 after the initial circuit thereto passing through the central segment 40 has been broken.

The further progress of the car to a point nearer the third floor effects the final transfer of the circuit to the index lamp 21 to a 25 path including the last segment 44, the path being traceable as follows: from the plus feed thru conductor 105, index lamp 21, conductor 115, brush 31, conducting segment 44, brush 30, circuit holding conductor 117, and 30 thence back to the negative feed by way of switch 100 and conductors 121 and 122.

It is, therefore, apparent that the initial brush 30 and the auxiliary conductor 117 constitute the means for holding circuits completed to each of the index lamps as the elevator progresses, this being accomplished thru the medium of the elongated segment 44, to which segment each of the circuits is successively shunted after its initial closing thru 40 the instrumentality of the central segment 40 and the intermediate temporarily bridging segment 42. Thus, when the parts have have reached the position shown in Fig. 4, for example, (which position they reach when 45 the elevator arrives at the fourth floor in its upward travel) the elongated segment 44, the initial brush 30, and the conductor 117 coat to maintain circuits to the index lamps 20, 21 and 22 while the central segment 40, coating 50 with the brush 33, has just effected a closing of the circuit to the index lamp 23 representing the fourth floor.

Now, should the elevator reverse at the 55 fourth floor and start to descend again there will be a prompt extinguishing of the lights 20, 21 and 22, a continuation of the illumination of the light 23, and a prompt illumination of the lamps 24 to 27 inclusive to produce the effect shown in Fig. 5. The prompt extinguishing of the lamps 20, 21 and 22 is caused by the resulting shifting of the switch member 75 to the position indicated in Fig. 5, thereby breaking the circuits which had theretofore been maintained to the lamps 20, 60 21 and 22 thru the instrumentality of the

switch fingers 101 and 102. The continuation of the illumination of the index element 23 results from the fact that the circuit thereto—as is always the case with the circuit to the foremost lamp representing the floor which the elevator is nearest—follows a path which does not include the switch member 75, and which, therefore, is unaffected by any movement thereof. Finally, the circuits to the index lamps 24 to 27 inclusive are closed by reason of the engagement of the surface 100 of the switch member 75 with the fingers 133 and 134 controlling the circuits to the brushes 34 to 37 inclusive, which in turn govern the operation of the lamps 24 to 27 inclusive.

From the foregoing it is apparent that a circuit is always maintained to the index element representing the floor nearest to the elevator while at the same time circuits are likewise maintained to the index elements representing all floors between such floor and the terminal away from which the elevator is traveling. The effect is to produce a column of illumination, the head of which indicates the floor nearest the elevator at a given time and the direction of the expansion of the column indicating the direction of travel of the elevator.

Various modifications may be made in the construction, arrangement and application of the parts without departing from the scope of the invention as disclosed herein, and as defined in the appended claims. Thus for example, in place of the switch construction shown in Fig. 3, any other suitable circuit shifting device, such as a set of mercury cups or tubes may be employed; similarly other types of reversing mechanism may be substituted for the friction operating mechanism of Figures 7, 8 and 9. Likewise the indicator panel may be placed in the elevator itself or in locations other than those shown in Fig. 1, and other types of indicating units such as electromagnetic targets may be substituted for the electric lamps.

I claim.

1. A circuit controller comprising a pair of current conducting segments, a series of current conducting brushes, means for rendering said brushes engageable successively with said segments, contact means intermediate said pair of segments for connecting the first or last of said series of brushes at all times to a source of current, means for feeding current through the first brush and one of said segments, from all other brushes, during relative movement of said brushes and said segments in one direction, and means for feeding current through the last brush and the other of said segments, from all other brushes during relative movement in the opposite direction.

2. A circuit controller comprising a source of current, a pair of conducting segments, and means for connecting said segments to

said source alternately, said means comprising a series of brushes and means for rendering said brushes engageable successively with said segments, conductors permanently connecting each of said brushes with one side of said current source, and contact means intermediate said pair of segments for alternately connecting the first and last brushes of said series with the opposite side 5 of said current source, and thereby energizing the segment with which the first or last brush is engaged, the current passing through said first or last brush and said segment in series, and through the remaining brushes in parallel, by way of said first named conductors.

3. A circuit controller comprising in combination with the apparatus defined in claim 2, additional means for energizing said first brush when not in engagement with either of said segments, said means including one 20 of said first named conductors.

4. A circuit controller comprising in combination with the apparatus defined in claim 2, additional means for energizing said first and last brushes when not in engagement with either of said segments, said means including a third current conducting segment 30 interposed between said pair of segments and engageable with each brush in sequence, and a connection from said segment to said current source.

5. A circuit controller comprising a source 35 of current, a pair of conducting segments, and means for connecting said segments to said source alternately, said means comprising a series of brushes and means for rendering said brushes engageable successively with said segments, conductive permanently connecting each of said brushes with one side of said current source, additional conductors for energizing the segments when the first or last brush of said series is in engagement therewith, the current passing 40 through said first or last brush and said segment in series, and through the remaining brushes in parallel, by way of said first named conductors, and means for energizing said first brush independently of either of 45 said segments when not engaged therewith.

6. Apparatus as defined in claim 5, wherein in the last named energizing means includes a third current conducting segment interposed between said pair of segments and engageable with each brush and sequence, and a connection from said segment to said current source.

7. Apparatus as defined in claim 5, wherein in the last named energizing means includes a third conducting segment interposed between said pair of segments and engageable with each brush in sequence, a connection from said segment to said current source, and a fourth conducting segment also interposed between said pair of segments, and

connected electrically to said source only during relative movement of said brushes and segments in one direction.

8. Apparatus as defined in claim 1, wherein in the current feeding means includes a 70 switch in circuit with said brushes, a lever for shifting said switch and common means for moving said segments and shifting said lever.

Signed at Hoboken in the county of Hudson and State of New Jersey this fifth day of June A. D. 1928.
